(57) **CLAIM**

The ornamental design for an electric scooter, as shown and described.

DESCRIPTION

FIG. 1 is an end upper perspective view of the electric scooter showing my design with portions indicated for later enlarged view in subsequent figures.

FIG. 2 is a lower perspective view thereof, showing a portion indicated for a later enlarged view in a subsequent figure.

FIG. 3 is a front elevation view thereof.

FIG. 4 is a back elevation view thereof, showing a portion indicated for a later enlarged view in a subsequent figure.

FIG. 5 is a side elevation view thereof.

FIG. 6 is an opposite side elevation view thereof.

FIG. 7 is a top plan view thereof.

FIG. 8 is a bottom plan view thereof.

FIG. 9 is an isolated perspective view of a portion 9 indicated in FIG. 1 as an end of a handle.

FIG. 10 is an isolated perspective view of a portion 10 indicated in FIG. 1 as a middle of the handle, showing features in broken lines.

FIG. 11 is an isolated perspective view of a portion 11 indicated in FIG. 1 as a front wheel, showing features in broken lines.

FIG. 12 is an isolated perspective view of a portion 12 indicated in FIG. 2 as a front bar junction, showing features in broken lines; and,

FIG. 13 is an isolated perspective view of a portion 13 indicated in FIG. 4 as a partial back side of the handle. The dash-dot broken lines are included to annotate partial views in FIGS. 1, 2, 4 and 9-13. All other broken lines represent portions of the electric scooter that form no part of the claimed design. None of the broken lines form a part of the claim.

1 Claim, 13 Drawing Sheets
